MULTIPLEX CORRECTION CIRCUIT

Filed Oct. 4, 1938

FIG. 1.

FIG. 2.

UNITED STATES PATENT OFFICE

2,265,843

MULTIPLEX CORRECTION CIRCUIT

Mark B. Kerr, Rosebank, Staten Island, N. Y., assignor to Postal Telegraph-Cable Company (New York), New York, N. Y., a corporation of New York

Application October 4, 1938, Serial No. 233,170

8 Claims. (CL 178—53)

My invention relates to a multiplex telegraph arrangement and more particularly to a corrector circuit for such multiplex systems.

In multiplex arrangements it is necessary that the distributors at repeater stations or terminal sets be maintained in rotation substantially in synchronism with the distributor at the sending station. For this reason it is the usual practice to provide some means for correcting the speed of rotation of a distributor in accordance with the received signals and under control of such signals. A number of arrangements for this purpose utilizing a tuning fork for driving a phonic motor or other suitable means have been quite commonly used. In all of these systems a correcting commutator is provided cooperating with the receiving distributor. This commutator in general is composed of two conducting segments for each of the segments of the receiving distributor. Alternate ones of these corrector commutator segments are connected to a suitable relay or relays through the common ring of the commutator so as to provide the proper speed or phase control. According to the systems used generally in the prior art it is common practise to provide a combination of relay or relays and condensers to produce the desired correcting impulses so that the discharge of the condenser may be used to test the phase of the brushes.

In accordance with my invention a corrector circuit similar to that described above is utilized. However, I provide an arrangement in which a single neutral relay may be used for the purpose of producing the impulses. This neutral relay is so connected as to produce an impulse upon every reversal of line current. By use of this arrangement the corrections may be made utilizing simpler equipment than was used in the prior art. Furthermore, the neutral relay arrangement has operational characteristics which constitute a distinct improvement over the systems utilizing polar relays.

It is an object of my invention to provide a corrector system which is positive in operation and is simpler in construction than those known in the prior art.

It is a further object of my invention to provide a correcting arrangement in which a neutral relay is utilized to generate the equivalent of the rectified first derivative of the line signals.

It is a further object of my invention to provide an arrangement which is independent of relay bias and will function over a wide range of adjustments.

It is a still further object of my invention to

provide a neutral relay arrangement wherein the release time of the neutral relay is used to produce a correcting or synchronizing impulse.

It is a still further object of my invention to provide an arrangement utilizing a neutral relay provided with a biasing winding in which the correcting impulse duration is determined by the overlap period of a make before break contact adjustment on said relay.

Other objects and advantages of my invention will be apparent from the particular description of my invention in connection with the accompanying drawing, in which—

Fig. 1 illustrates a schematic arrangement of a corrector circuit in accordance with my invention, and

Fig. 2 discloses an alternative arrangement of a corrector circuit utilizing the principles of my invention.

Turning first to Fig. 1, I show a main line relay 101 provided with a contact armature arrangement 102. This main line relay operates to reproduce the received signals for transmission to the usual distributor segments for the received signals as well as for producing the corrector impulses. Since the signal portions of the distributor do not constitute a part of this invention, these features have not been illustrated. It is well known that in the usual multiplex line im-

pulses of positive and negative current are utilized in various groups to designate the separate characters. These signals are received over the line and serve to operate the polarized line relay 101. Operation of the line relay causes a reversal

of the connection of contact tongue 102 with respect to a local source indicated at the upper part of the drawing by the plus and minus sign. Accordingly each reversal of the line signal causes a reversal of polarity of the current traversing

winding 103 of relay 104. This relay 104 is a neutral relay and therefore each reversal of direction of the current causes the relay to release and reoperate. Upon each release of the relay its armature 105 closes a contact to ground for the common ring 111 of correcting commutator 110.

This circuit to ground is closed only momentarily since the relay 104 immediately reoperates breaking the ground contact. The time duration of the correcting impulse may be varied between predetermined limits by adjusting the tension of spring 106. The usual printer relay may be inserted in the lead of winding 103 at a suitable point, if desired. However, since this particular arrangement forms no part of my invention detailed illustration is omitted.

Commutator 110 is provided with a common ring 111 and a plurality of segments 112 marked F and S in the drawing. These segments are alternately arranged and all of the F and S segments respectively, are separately connected together. A brush 113 is provided to complete the circuit from the separate segments to the common ring, or may constitute the common grounded connection for the two halves of the commutator. A correcting relay 120, preferably a two-winding unbiased polarized relay, is provided, winding 121 of which is connected to the common lead of the S segment and through the winding 121 to a positive supply and winding 122 of which is connected from the common lead of the F segment through the winding 122 to the positive supply. Windings 121 and 122 are arranged so as to operate their common armature 123 respectively in opposite directions. For example, when a circuit is completed from positive battery through winding 122 contact F of distributor 110, brush 113 and common ring 111, contact 105 to ground, the corrector relay armature 123 is moved to the position shown in the drawing. In this position a negative potential is applied through 123, the corrector switch 125, a meter 126 and winding 128 of correcting magnet 127 to ground. This energization of correcting magnet 127 serves to increase the speed of a tuning fork 130. The tuning fork is connected to control some suitable phase correcting means over leads 130'. The increased speed of the tuning fork is preferably adjusted to drive the distributor at a speed slightly above the transmitting speed so that the distributor tends to gain with respect to the signals. The correcting means may be of any suitable type, for example a phonic wheel, but since the particular type of arrangement used constitutes no part of the invention these parts have not been specifically illustrated.

If, at the time relay 104 releases, the brush 113 is across at one of the S segments, a circuit is established from positive, winding 121 of relay 120, S segments, brush 113, contact 105 to ground. This connection serves to throw relay contact armature 123 to the right, opening the circuit of corrector magnet 128 to thus slow down the fork 130 and consequently reduce the speed of the distributor. The distributor will then tend to lag with respect to the received signals and will continue to slow down until it has reached such a position that the brush 113 closes a contact through the F commutator segments, returning the contact armature 123 to the left position. The distributor then tends to slowly gain with respect to the received signals and the cycle is repeated. Since operation of the line relay determines the relative timing at which the distant sending distributor is passing from one segment to the next, each correction impulse developed by the neutral relay establishes the time at which the correction brush should be passing from an F to an S segment. Thus by using the circuit as described above the phase of the distributor will be continually tested and the average speed will be held exactly equal to that of the distant sending distributor.

In Fig. 2 is illustrated an alternative arrangement in accordance with my invention for utilizing a biased neutral relay to produce the correction action. In this figure the parts of the circuit corresponding with those of Fig. 1 have been similarly numbered.

As fully described in connection with Fig. 1, the correction impulses are impressed by means of a commutator 110 having segments marked F and S. Since the operation of the corrector circuit itself and the corrector magnet is the same as in Fig. 1, this portion of the circuit has not been fully illustrated and the operation of the system will not be described in detail. It is clear that the circuit of Fig. 2 may be used to replace the corresponding parts of the circuit in Fig. 1.

In this arrangement, however, I provide on relay 104 an additional biasing winding 201 and in place of the armature of the type shown in Fig. 1, I use with relay 104 an armature 205 in the form of a make before break switch. Also in Fig. 2 I have shown a connection through winding 103 of corrector relay 104 directly to the winding of the usual printer relay 201'. This printer relay operates to repeat the received signals through to suitable printing apparatus or a transmitting distributor dependent upon the nature of the circuit with which the correcting means is associated.

Turning more specifically to the details of the corrector control relay shown in Fig. 2, it will be noted that the connection of common ring 111 to ground must occur through the operation of armature 205 at the time that the ground contact 2 is made and before the circuit with contact 1 is broken. The correction impulse can only be developed when the armature 205 is properly adjusted to make one side before breaking the other and the duration of the impulse depends on the overlap time of 205. This can be varied by adjustment to produce impulses of sufficient duration for satisfactory operation of the corrector relay. The biasing winding 201 in conjunction with negative potential through 102 serves to generally maintain armature 205 in the position illustrated. Upon change of polarity of the signal by receipt of a positive signal impulse, armature 102 moves over to the positive side, and relay 104 will release since this added positive current is connected to oppose the biasing current. Upon the release of 205 a contact is made with 2 before it is broken at 1. During the short period of time that this condition exists an impulse is applied to the common ring 111 of the commutator 110. Switch 205 will then remain in the released position until another line signal of negative polarity arrives so as to again reverse the connection of contact 102. Upon reversing contact 102 to the negative side, relay 104 will again operate returning armature 205 to the left. As the armature 205 moves to the left contact 1 is made before contact 2 is broken and another correcting impulse is impressed on common ring 111 of the corrector relay. It is thus clear that each reversal of the line current may serve to impress a correcting impulse through commutator 110 upon corrector relay 120. The nature of this correcting impulse will depend upon the speed of the distributor and its particular phase relation at the time the impulse is impressed. The time duration of the correcting signal may be adjusted by changing the period of overlap of make-before-break contacts 205, 1 and 2. Thus a control of the speed of the distributor to maintain it in substantial synchronism is produced as described more specifically in connection with Fig. 1.

While I have disclosed particular arrangements of a corrector circuit to illustrate my in-

vention, it should be distinctly understood that these illustrated embodiments constitute merely a disclosure of certain preferred forms and should not be considered as defining the scope of my invention. What I consider to be my invention and upon which I desire to secure protection is defined in the appended claims.

I claim:

1. A telegraph signal corrector circuit for systems using reverse polarity signals comprising a corrector relay, means controlled by said corrector relay for determining a speed, a commutator having segments connected to said corrector relay, means for completing a circuit between said segments and ground for operating said corrector relay comprising a neutral relay operative in response to each change in polarity of said signals, and contact means controlled by said relay for connecting said segments to ground.

2. A corrector circuit comprising means responsive to signal impulses for applying potentials of different polarity to a circuit, means in said circuit operative upon every change of polarity to alternatively release or to reclose dependent upon the applied polarity, and make-before-break means operative upon every release and every reclosure of said last named means for producing a correcting impulse of a predetermined time duration.

3. A telegraph system comprising a polarized line relay operative in response to received signals of different polarity, an armature moved by said line relay into one of two positions depending upon the polarity of said signals to connect current sources of different polarity thereto, a neutral relay having a winding connected to said armature, and a polarized corrector relay operative by impulses from said neutral relay for applying speed correction.

4. A corrector system comprising a polarized line relay responsive to telegraph signals of different polarity, a biased neutral relay, means for energizing said relay with current the polarity of which depends on the nature of said telegraph signals in response to operation of said line relay, a corrector circuit and make-before-break contact means controlled by said biased neutral relay for applying a correcting impulse of predetermined duration to said corrector circuit in response to every change in polarity of said line signals.

5. In a correction circuit for a synchronously operating multiplex printing telegraph system, the combination of a line relay, a neutral relay controlled by said line relay to release and re-operate upon every operation of said line relay, a distributor comprising a plurality of correcting

segments, a differential polarized correcting relay connected to said correcting segments, and means jointly operable by said neutral relay and said correcting segments for causing differential operation of said correcting relay.

6. In a correction circuit for a synchronously operating multiplex printing telegraph system, the combination of a line relay, a neutral relay controlled by said line relay to release and re-operate on every operation of said line relay to generate a series of impulses each of predetermined substantially equal time duration, a distributor comprising a plurality of correcting segments, a differential polarized correcting relay connected to said correcting segments, and means jointly operable by said neutral relay and said correcting segments for causing differential operation of said correcting relay.

7. In a correction circuit for a synchronously operating multiplex printing telegraph system, the combination of a line relay operating on incoming signals according to an equal element permutation code, a neutral relay controlled by said line relay to release and re-operate upon every operation of said line relay to generate a series of impulses each of a time duration equal to a fractional part of the unit elements of said incoming signals, a distributor comprising a plurality of correcting segments, a differential polarized correcting relay connected to said correcting segments, and means jointly operable by said neutral relay and said correcting segments for causing differential operation of said correcting relay.

8. In a correction circuit for a synchronously operating multiplex printing telegraph system, the combination of a line relay, a neutral relay controlled by said line relay to release and re-operate upon every operation of said line relay, a distributor comprising a plurality of correcting segments and a common segment, means for applying ground to said common segment upon each release of said neutral relay, a polarized corrector relay having a first winding connected to alternate ones of said correcting segments and a second winding connected to the remaining correcting segments, means for driving said distributor, and a correcting brush driven by said driving means and effective jointly with said neutral relay to apply ground to one or the other winding of said correcting relay in accordance with phase variations, and means under control of said correcting relay for increasing or diminishing the speed of operation of said driving means.

MARK B. KERR.
